[57] CLAIM

The ornamental design for a cordless electric tool, as shown and described.

DESCRIPTION

FIG. 1 is a side elevational view of a cordless electric tool.

FIG. 2 is a front elevational view of the tool shown in FIG. 1.

FIG. 3 is a top plan view of the tool shown in FIG. 1.

FIG. 4 is a bottom plan view of the tool shown in FIG. 1.

FIG. 5 is a rear elevational view of the tool shown in FIG. 1.

FIG. 6 is a perspective view of another embodiment of a cordless electric tool.

The portions of this embodiment not shown in this view are identical to those shown in FIGS. 1—5 except that the gripping surface texture illustrated therein is omitted.

FIG. 7 is a side elevational view of another embodiment of a cordless electric tool.

FIG. 8 is a side elevational view of a third embodiment of a cordless electric tool.

FIG. 9 is a top plan view of the tool illustrated in FIG. 8.

FIG. 10 is a bottom plan view of the tool illustrated in FIG. 8.

FIG. 11 is a front elevational view of the tool shown in FIG. 8.

FIG. 12 is a rear elevational view of the tool shown in FIG. 8.
